ELECTRIC WATER HEATER

Filed Sept. 13, 1946

UNITED STATES PATENT OFFICE

2,572,337

ELECTRIC WATER HEATER

William B. Harris, Bell, Calif.

Application September 13, 1946, Serial No. 696,698

5 Claims. (Cl. 219—40)

1

This invention relates to an instantaneous water heater, and particularly to one in which the heating is effected by the passage of current through the water.

Heaters of this character usually employ spaced carbon electrodes between which the water circulates. These electrodes may be flat plates or circular.

In many installations, it is desirable readily to adjust the temperature of the water at the outlet.

It is one of the objects of this invention to make it possible, in a simple manner, to adjust the spacing of the electrodes for effecting this result.

It is another object of this invention to provide an improved form of heater of this general character.

This invention possesses many other advantages, and has other objects which may be made more clearly apparent from a consideration of one embodiment of the invention. For this purpose there is shown a form in the drawings accompanying and forming part of the present specification. The form will now be described in detail illustrating the general principles of the invention; but it is to be understood that this detailed description is not to be taken in a limiting sense, since the scope of this invention is best defined by the appended claims.

Referring to the drawings:

Figure 1 is a vertical section of a heater incorporating the invention; and

Fig. 2 is a partial sectional view, taken along the plane indicated by line 2—2 of Fig. 1.

The heater includes a stationary electrode 1 made of carbon or graphite. This electrode is shown as having a cylindrical exterior surface and a conical active electrode surface 2. A cooperating electrode 3, which may also be made of carbon or graphite, is shown as having an active, conical electrode surface 4. The axis of the two conical surfaces are coincident, and the slopes of the cones are identical. This common axis corresponds to the axis of the housing 5 in which the electrodes are accommodated.

The housing 5 is also shown as cylindrical, and is preferably made in two parts to facilitate assembly of the heater. The lower part 6 of the housing may be made from insulation material, such as Bakelite, or the like. The electrode 1 rests upon the bottom surface 7 thereof. A number of screws, such as 8, pass through the bottom and engage threaded apertures in the bottom of the electrode 1 to hold it firmly in place. One

2

of these screws can serve as a terminal for a source of supply, connection to which is made by the aid of a lead 9.

The upper part 10 of the housing 5 is also made of insulation material similar to that utilized for the lower part 6. It has a depending flange 11 contacting the upper edge of the part 6.

The parts are held firmly together by the aid of a jacket structure formed, in this instance, of metal. The inner wall 12 of this jacket structure may be formed as a tubular element with an upper flange 13. This tubular element closely encompasses the exterior cylindrical surfaces of the parts 6 and 10. The outer wall 14 of the jacket structure defines with inner wall 12, an annular space 15. The two walls 12 and 14 may be joined together as by welding, as indicated at 16.

The outer wall 14 has an inwardly turned flange 17 engaging the lower surface of the housing member 6.

In order to hold the parts firmly together, a clamp ring 18 is utilized. Through the clamp ring 18 and the flange 13 a number of bolts 19 are provided. In order to render the housing fluid-tight, the upper and lower edges of the housing 5 are bevelled, as indicated at 20, for the accommodation of the circular compressible gaskets 21. The upper gasket 21 is accommodated in the space formed between the clamp ring 18, the housing member 10, and the inner wall 12.

The lower gasket 21 is similarly accommodated in the space formed between the flange 17, the inner wall 12, and the housing member 6.

The inlet to the space 22, formed between the electrodes 1 and 3, is provided by the aid of a number of slots or apertures 23 disposed in the top edge of the housing member 6. These openings are in communication with the annular space 15, as by appropriately formed apertures 24 in the inner wall 12. Connected to the lower portion of the jacket is an inlet pipe 25. This inlet pipe 25 is shown, as having an exteriorly threaded portion, to accommodate an appropriate coupling leading to a source of cold water supply. The amount of flow may be regulated by a needle valve 26 threaded transversely through the pipe 25. This needle valve interposes an adjustable barrier to the flow of water through the inlet passage 27. The pipe 25 may be appropriately welded to the exterior wall 14.

The outlet pipe 28 is shown as extending through the outer wall 14 of the jacket, and attached, as by welding, to both the inner and

outer walls of the jacket. It may be provided with interior and external threads for an appropriate coupling for the discharge of the heated water through the discharge opening 29. This discharge opening communicates with the aperture 31 arranged radially in the bottom of housing member 6. This aperture 31 leads to the lower portion of the space 22 between electrodes 1 and 3.

The path of the water, therefore, is a somewhat tortuous one. The incoming water passes through the inlet opening 21, thence upwardly through the space 15, through the openings 24 and 23, thence downwardly through the space 22, and out to the discharge opening 29 by way of the radial aperture 31.

The electrode 3 is arranged to be adjusted along its axis to vary the spacing between the active surfaces 2 and 4 of the electrode. In this way, the amount of electrical energy converted into heat may be controlled and thereby the outlet temperature of the water may be determined.

In order to adjust the electrode 3, it is mounted upon a metal stem 32. This stem 32 has a lower cylindrical portion 33 rotatably mounted in a boss 34 provided in the bottom of the housing member 6. The stem 32 is threaded, and the electrode 3 is firmly mounted on the threads and prevented from relative rotation with respect to the stem 32. The upper threaded portion of the stem 32 is in engagement with the internal threads 34 of a conducting member 35 which may be made of brass, or the like. This conducting member 35 is firmly attached to the cover 10, as by the aid of the annular groove 36 in which the cover or top 10 is molded.

In order to adjust the height of electrode 3, the stem 32 may be rotated so that the upper part of the stem is threaded into or out of the member 35. Since the stem 32 is made of metal, the connection to the electrode 3 may be readily effected by the aid of a terminal 37 fastened, as by a screw 38, to the upper sloping wall of member 35.

The stem 32 is provided with an extension 39 which passes out of the housing and which is provided with a non-circular end 40, facilitating the use of a wrench for angularly moving the stem 32. In order to provide against leakage past the extension 39, the member 35 has a hollow extension 41 for accommodating a cylindrical, compressible packing member 42. This packing member closely surrounds extension 39. It rests upon a washer 43 above the threaded portion 34. The packing is compressed by the aid of the packing gland nut 44 threaded on the exterior of the portion 41. A washer 45 is inserted between the nut 44 and the top of the packing 42.

Upon rotation of the stem 32, the width of the space 22 can be readily adjusted. Since the slopes of the conical surfaces 2 and 4 are identical, the space 22 between these surfaces remains uniform, all around the electrodes, for all adjustments of electrode 3. Furthermore, it is to be noted that, upon adjustment, the electrode 3 rotates with the stem 32. Thus, there is relative angular motion between the active surfaces 2 and 4 upon adjustment of the electrode 3. In this way, any tendency for the surfaces to develop substantial irregularities over long periods of operation is reduced, since new portions of the surface 4 are presented to the cooperating surface 2.

To facilitate assembly of the heater, the inner wall 12 of the jacket may be tapered so that its upper end has a slightly larger diameter than its lower end, the outer and inner surfaces of the housing 5 being correspondingly tapered, as is also the outside surface of the stationary electrode 1. For example, the upper end of the inner wall 12 may have an inside diameter of 3.750", the outer jacket wall having a uniform diameter of four inches. In this way, insertion of the electrode 1 into the lower part 6 of the housing is facilitated, as well as the insertion of lower part 6 and the upper part 10 of the housing into the jacket.

The inventor claims:

1. In a liquid heater: a housing made from insulation material; an electrode fastened in the housing and having an active surface of revolution generated by a line oblique to the axis of revolution; a cooperating electrode having an active surface of revolution uniformly spaced from said first surface; means for adjusting said cooperating electrode along the axis of revolution; and means forming an annular space on the exterior of the housing and in communication with the interior of the housing.
2. In a liquid heater: a housing made from insulation material; an electrode fastened in the housing and having an active surface of revolution generated by a line oblique to the axis of revolution; a cooperating electrode having an active surface of revolution uniformly spaced from said first surface; means for adjusting said cooperating electrode along the axis of revolution; 30 there being one or more openings in the housing above the electrodes; means forming an annular space around the housing and communicating with the electrodes; means forming an inlet to the annular space; and means forming an outlet from the space between the electrodes.
3. In a liquid heater: a housing made from insulation material; an electrode in the bottom of the housing and having an internal conical active surface, the axis of the surface being substantially vertical; a cooperating electrode having an external conical active surface, coaxial with the internal surface and having the same slope; a stem carrying the cooperating electrode and having threads at its upper portion, said stem having an extension projecting from the top of the housing; means carried by the top of the housing in which the threads engage, for causing the stem to move axially when rotated; and means forming an annular space around the housing and in communication with the housing adjacent the top of the housing.
4. In a liquid heater: a hollow housing of insulation material having a separable top portion; an electrode having an interior conical active surface having an axis extending substantially vertically and carried at the bottom of the housing; a cooperating electrode coaxial with said first electrode and having an exterior active conical surface of the same slope as the interior surface; a stem carrying said second electrode and having an extension projecting out of the top of the housing; a metallic member carried by the top of the housing and in threaded engagement with the stem; means forming a jacket around the housing, said jacket having an inlet communicating with the interior of the housing adjacent the top thereof, said jacket serving as a casing for the housing; and clamping means for holding the housing in the casing.
5. In a liquid heater: a housing made from

insulation material; an electrode fastened in the housing and having an active surface of revolution generated by a line oblique to the axis of revolution; a cooperating electrode having an active surface of revolution uniformly spaced from said first surface; means for adjusting said cooperating electrode along the axis of revolution; means, exterior of the housing and cooperating with the housing to form an annular space around said electrode which is fastened in the housing, there being one or more openings above the electrodes establishing communication between said annular space and the space between the electrodes; means forming an inlet to the annular space; and means forming an outlet from the space between the electrodes.
